UNITED STATES PATENT OFFICE.

WILLIAM JOHN TWISS, OF CALGARY, ALBERTA, CANADA, ASSIGNOR OF ONE-HALF TO
JOHN I. McFARLAND, OF CALGARY, ALBERTA, CANADA.

PIPE WRENCH.

1,407,238.

Specification of Letters Patent. Patented Feb. 21, 1922.

Application filed June 22, 1921. Serial No. 479,634.

To all whom it may concern:

Be it known that I, WILLIAM JOHN TWISS, a subject of King George of Great Britain, and residing at Calgary, in the Province of Alberta, in the Dominion of Canada, have invented certain and useful Improvements in a Pipe Wrench, of which the following is a specification.

In my invention it is sought to provide an easily placed pipe wrench which will be self adjusting to a number of different sizes of pipes, the amount of adjustment necessary for various size of pipes being reduced to the minimum.

I accomplish these objects by the device illustrated in the accompanying drawing, in which—

Fig. 1 is a perspective view showing the wrench in position for use.

Fig. 2 is a perspective view of the pivoted jaw.

Fig. 3 is a perspective view of the member for holding the jaws in relation to one another when the wrench is in use.

Similar characters designate similar parts throughout the several views. *a* is a shank which serves as a handle formed integral with which is a jaw *b*, the underside of which jaw is provided with a serrated edge *c*. The end of the jaw *b* remote from the shank is bifurcated as shown at *d* and in this bifurcated end, one end *e* of a lower or second jaw *f* is pivoted with a pin *g*.

The jaw *f* is bent downwardly so as to leave a space between its upper surface and the lower surface of jaw *b*, this space being tapered and of any suitable size. The end of the jaw *f*, remote from the pivot extends underneath the shank for a short distance as shown at *h*, and is held adjacent to the shank by a substantially rectangular member *i* pivoted at the junction of the shank *a* and the jaw *b*. This rectangular member *i* has an adjusting screw *k* which is adapted to bear upon the under surface of the extended end *h* of the jaw *f*. A pipe is held by friction and pressure between the serrations *c* upon the upper jaw *b* and the interior surface of the lower jaw *f*, the rectangular member *i* holding the two jaw members adjacent to one another.

Having now described my invention, what I claim is:

1. A pipe wrench of the class described

comprising a shank having one end offset to form an upper jaw, such jaw being provided with a bifurcated end a plurality of teeth extending transversely across the under face of the said upper jaw, a lower jaw adapted to be pivotally connected to the said bifurcated end, a catch member substantially rectangular in shape having a slot therethrough such slot being pivoted to the said shank and adapted to engage with the free end of the said lower jaw and means engaging with the said catch member adapted to control the adjustment of the said lower jaw relatively to the upper jaw.

2. A pipe wrench of the class described comprising a shank having one end offset to form an upper jaw, such jaw being provided with a bifurcated end, a plurality of teeth extending transversely across the under face of the said upper jaw, a lower jaw adapted to be pivotally connected to the said bifurcated end, a catch member substantially rectangular in shape having a slot therethrough adapted to be pivoted to the said shank and having a threaded orifice extending through the upper end thereof, such slot being adapted to engage with the free end of the said lower jaw and a set screw designed to make threaded engagement with the said threaded orifice, as and for the purpose specified.

3. A pipe wrench of the class described comprising a shank having one end offset to form an upper jaw, such jaw being provided with a bifurcated end, a plurality of teeth extending transversely across the under face of the said upper jaw, a lower jaw adapted to be pivotally connected to the said bifurcated end, the other end of the said lower jaw being bent downwardly, a catch member substantially rectangular in shape having an upwardly extending slot therethrough, and having a threaded orifice through the top member thereof, such slot being designed to be pivoted to the lateral side of the said shank, the lower end of the said slot being designed to engage with the free end of the lower jaw and a set pin designed to engage with the said threaded orifice, as and for the purpose specified.

WILLIAM JOHN TWISS.
